UNITED STATES PATENT OFFICE.

RUBY T. BREWSTER, OF NEW YORK, N. Y.

DESIGN FOR AN ATOMIZER.

Application filed April 22, 1927. Serial No. 21,681. Term of patent 3½ years.

To all whom it may concern:

Be it known that I, RUBY T. BREWSTER, a citizen of the United States, residing at New York city, in the county and State of New York, have invented a new, original, and ornamental Design for an Atomizer, of which the following is a specification, reference being had to the accompanying drawing, forming part thereof.

Fig. 1 is a plan view; and

Fig. 2 is a front view, showing my new design.

I claim:

The ornamental design for an atomizer, as shown.

RUBY T. BREWSTER.
